H. A. STILLWELL

DRILLING APPARATUS FOR SHELLS

Filed July 24, 1916.

Inventor

Howard A. Stillwell

By his Attorney

Prindle, Wright & Searle

UNITED STATES PATENT OFFICE.

HOWARD A. STILLWELL, OF WOODBURY, NEW JERSEY, ASSIGNOR TO E. I. DU PONT DE NEMOURS AND COMPANY, OF WILMINGTON, DELAWARE, A CORPORATION OF DELAWARE.

DRILLING APPARATUS FOR SHELLS.

Application filed July 24, 1916. Serial No. 110,886.

To all whom it may concern:

Be it known that I, HOWARD A. STILLWELL, a citizen of the United States and a resident of Woodbury, in the county of Gloucester and in the State of New Jersey, have invented a certain new and useful Improvement in Drilling Apparatus for Shells, and do hereby declare that the following is a full, clear, and exact description thereof.

10 My invention relates particularly to an apparatus designed for drilling holes in the explosive charges contained in shells, so that primers or other charges may be inserted in said holes, although my invention is adapted to drilling for other purposes.

The object of my invention is to provide an apparatus, by means of which holes of the above character may be readily drilled, and in such a manner that the borings fall 20 away by gravity. A further object of my invention is to provide an apparatus of this character which is simple in construction, and which operates so as to feed the shell automatically to the drill while the shell 25 is being rotated.

While my invention is capable of embodiment in many different forms, for the purpose of illustration I have shown only one form thereof in the accompanying drawings, 30 in which,

Fig. 1 is a side elevation of an apparatus made in accordance with my invention; and

Fig. 2 is a vertical section of the shell-holding means in the same.

35 In the drawings I have shown a base 1, having thereon an upright 2 provided with a flange 3 in such a manner that said flange extends to either side of the upright 2. Sliding on said upright 2 there is a bracket 4 adapted to be held in place by a cam 5, operated by a handle 6. Said bracket carries in its end a stationary drill 7 having 40 projecting from the side thereof a cutter 8 for producing a counter-sink in the shell.

45 A gauge 9 attached to the bracket 4 determines the depth of the hole to be bored in the shell. At the rear of the upright 2, there is a shaft 10, having a driving pulley 11 thereon driven from any suitable source 50 of power, said driving pulley being connected to a pulley 12 for driving a belt 13 adapted to be moved over the same. A loose

pulley 14 is also located on the shaft 10 to receive the belt 13 when the apparatus is thrown out of operation. Said belt 13 55 passes over two idler pulleys 14^a carried on a bracket 15 at the top of the upright 2, and thence around a pulley 16, which is splined to a slide 17 passing through the upper end of the bracket 15. Said slide 17 also passes through a lower bracket 18 extending laterally from the upright 2. The slide 17 is provided with a sleeve 18^a carrying a rack 19 which engages with a pinion 20 carried by a hand-wheel 21 journaled in the lower 60 bracket 18. Collars 21^a and 21^b retain the sleeve 18^a in place on the slide 17. On the lower end of the slide 17 there is fixed a collar 22, to which there is screw-threaded a cylinder 23. The collar 22 has a tapered recess 22^a for positioning the base of a shell. On the lower end of the cylinder 23 there is screw-threaded a cap 24 having a tapered opening 25 for engagement with the lower 65 tapered end of a shell 26, which is arranged 70 to be clamped in place by the same.

In the operation of my invention when a shell is to be inserted in the drilling apparatus, it being assumed that the belt 13 is located over the loose pulley 14, the hand-wheel 21 is operated to elevate the slide 17. The bracket 4 is also lowered by the operation of the handle 6. The cap 24 is removed and a shell is inserted in the cylinder 23, after which the cap 24 is screwed over the 80 end of the cylinder 23 so as to hold the shell 26 in place. Said shell 26 is accurately positioned in the middle of the cylinder 23 by reason of the tapered recess 22^a receiving the base of the shell and a tapered opening 25 85 engaging with the nose of the shell. The bracket 4 is then elevated until the end of the drill 7 is near the end of the shell 26. The belt 13 is now moved onto the driving pulley 12, and the hand-wheel 21 released so 90 as to permit the shell and the parts carrying the same to be fed by gravity against the drill 7. The hole in the explosive material carried in the shell is made by the drill 7 and the cutter 8, which produce a 95 hole with a countersink at the mouth of the same for receiving a primer or another explosive charge. The gauge 9 determines the 100 depth of the hole produced.

While I have described my invention above in detail, I wish it to be understood that many changes may be made therein without departing from the spirit of my invention, as defined in the following claims.

I claim:

1. A drilling apparatus for shells, comprising means to feed a shell downwardly in an inverted position, while rotating the shell, and a stationary drill co-operating with the same.

2. A drilling apparatus for shells, comprising means to feed a shell downwardly by gravity in an inverted position, while rotating the shell, and a stationary drill co-operating with the same.

3. A drilling apparatus for shells, comprising means to feed a shell downwardly in an inverted position, while rotating the shell, a drill co-operating with the same, and a support for said drill vertically adjustable toward and away from said shell feeding means.

4. A drilling apparatus for shells, comprising means to feed a shell downwardly by gravity in an inverted position, while rotating the shell, a drill co-operating with the same, and a support for said drill vertically adjustable toward and away from said shell feeding means.

5. In a device of the class described, a work holding member comprising an open ended cylinder adapted to contain a shell, and an annular cap for said cylinder adapted to support a shell therein.

6. In a device of the class described, a work holding member comprising an open ended inverted cylinder adapted to contain a shell, said cylinder having a centering incline adjacent the base thereof, and an annu-

lar cap for said cylinder adapted to support a shell therein.

7. Boring apparatus for recessing a tubular member, tapered at its forward end and comprising a boring tool, means for permitting relative reciprocation along a fixed path between the boring tool and the tubular member, and tapered means for engaging the tapered portion of the tubular member on opposite sides, to position the tubular member with respect to the path of reciprocation aforesaid. 45

8. Boring apparatus for recessing a tubular member tapered at the forward end and comprising a boring tool, means for permitting relative reciprocation along a fixed path between the boring tool and the tubular member, a support for the tubular member and a tubular stop for positioning the tubular member with respect to the path of reciprocation aforesaid, the tubular stop having a tapered internal bore adapted to fit the tapered end of the tubular member. 55

9. Boring apparatus for recessing a tubular member tapered at the forward end and comprising a boring tool, means for permitting relative reciprocation along a fixed path between the boring tool and the tubular member, a support for the tubular member and a tubular stop for positioning the tubular member with respect to the path of reciprocation aforesaid, the tubular stop having a tapered internal bore adapted to fit the tapered end of the tubular member, and having a threaded connection with the said support. 70

In testimony that I claim the foregoing I have hereunto set my hand.

HOWARD A. STILLWELL.
